A CORPORATION.

FEEDING DEVICE FOR PULVEROUS FUEL IN FURNACES FOR LOCOMOTIVES AND THE LIKE.

1,357,663.

Specification of Letters Patent. Patented Nov. 2, 1920.

Original application filed October 12, 1916, Serial No. 125,223. Divided and this application filed June 3, 1919. Serial No. 301,546.

To all whom it may concern:

Be it known that I, KARL HJALMAR VILHELM VON PORAT, subject of the King of Sweden, residing at Stockholm, Sweden, 5 have invented certain new and useful Improvements in Feeding Devices for Pulverous Fuel in Furnaces for Locomotives and the like, of which the following is a specification.

10 The present invention relates to such feeding devices for pulverous fuel in furnaces, where the powder is fed from a powder receptacle to the furnaces by means of a gaseous medium, which whirls up and 15 brings along with it a quantity of fuel to the furnace through a powder pipe or conduit, extending between the receptacle and the furnace.

20 The invention consists in certain improvements in the adjacent ends of the powder conduit and the gas or air supply pipe.

25 The invention is essentially characterized by the fact, that at the same time as the fuel transporting air current or currents is prevented from flowing in a straight line into the fuel outlet a member for covering the outlet of said air supply pipe is movable in relation to the discharge end of said pipe in such a way, that by adjusting one 30 of them the outlet of the air supply pipe can be covered or uncovered to any desired degree or wholly covered by said member. The said member forms preferably a part of the fuel pipe.

35 An embodiment of the invention is illustrated in the accompanying drawing. Figure 1 shows a longitudinal section of a tender for pulverous fuel with a feeding device according to the present invention.

40 Fig. 2 shows on a larger scale the device in the position for interrupted feed and Fig. 3 the same in the position for full feed. Only the lower part of the receptacle and the adjacent ends of the fuel and air pipes 45 located in said receptacle part are shown in Figs. 2 and 3.

50 In the embodiment shown the air current necessary for the feed is effected by means of pressure air supplied through the conduit 9.

That part of the fuel pipe 1 which is located in the powder receptacle 20 consists

of a metal pipe 2, which extends near and along the one of the two inclined and downwardly converging walls 21 of the receptacle 20. The discharge end of the air supply conduit 9, which is supplied with compressed air, is indicated by 4. This discharge end or pipe 4 projects into the receptacle from below and opposite the receiving opening of the fuel pipe, which opening forms the fuel outlet of the receptacle.

The pipe 2 is rotatably mounted in the receptacle in bearings 22, so that it can be 65 rotated around its own longitudinal axis by means of a handwheel 27 or the like, arranged on the outside of the receptacle. According to the embodiment shown the receptacle is arranged on a tender of a 70 locomotive, and in such a way, that the handle of the pipe 2 is conveniently accessible from the driver's cabin.

The lower edge of the pipe 2 lies in a plane, which forms an inclined angle to 75 the longitudinal axis of the pipe, so that the lower end of the pipe forms a tongue, or projection, which overlaps the pipe 4 on one side. The pipe 4, which tapers conically 80 toward its free end, is provided on the upper side with a plurality of fine holes 5.

Although the holes 5 thus are arranged laterally on the pipe 4 they are faced upward by reason of the tube 4 having an inclined position.

According as the pipe 2 is rotated to the one or other position the holes 5 are covered or uncovered to any desired degree by the lower end or projection of the pipe 2. In the position shown in Fig. 2 the holes 5 are 90 wholly covered by the end of the fuel pipe 2, and in the position shown in Fig. 3 the holes are wholly uncovered by the pipe 2. The former position is the position for entirely interrupted feed, and the latter position is the position for full feed.

Referring to Fig. 3 it will be understood, that by supplying pressure air through the conduit 9 air will flow out into and penetrate the powder mass in the receptacle 100 through the holes 5, so that the adjacent quantity of the powder mass will be whirled up and thereby partly on account of the pressure in 4 and partly on account

of the draft in the furnace will be forced or brought along with the air through the fuel conduit to the furnace. The pipe 4 has a central opening 8 at the point through which air is blown directly into the fuel pipe, whereby the blowing of the whirled up powder to the furnace through the fuel pipe is highly supported. On account thereof that the fuel transporting and whirling up air currents flowing out from the holes of pipe 4 are prevented from flowing in a straight line into the fuel pipe, the powder will be effectively whirled up and intimately mixed with air before escaping into the fuel pipe.

On account thereof that fuel pipe extends upwardly from its receiving end powder is prevented from falling by gravity into the fuel pipe. Thus no powder but that whirled up by the air currents from 5 can escape to the furnace.

According to the embodiment shown the powder feed is regulated by the angular adjustment of the pipe 2 without displacing said pipe endwise.

It is evident that the construction can be modified in such a way, that the pipe 4 instead of pipe 2 is made rotatable or both pipes can be angularly adjustable.

30 The pipe may in both cases lead directly from the atmosphere and the feed be effected only by means of suction into the powder pipe.

What I claim as new and desire to secure 35 by Letters Patent of the United States is:—

1. In a feeding device for pulverulent fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along with it a quantity of fuel from the receptacle through the fuel pipe, the adjacent end of the pipes being arranged in such way that the said fuel transporting air current is prevented from flowing in a straight line into the fuel outlet, a member for covering the outlet of said air supply pipe, said member and the discharge end of the air supply pipe being movable in relation to each other in such a way, that by adjusting one of them the outlet of the air supply pipe can be covered or uncovered to any desired degree by said member.

2. In a feeding device for pulverulent fuel for furnaces the combination of a powder receptacle, a fuel pipe extending from 60 said receptacle to the furnace, a pipe for supplying air or other gaseous medium into the mass in said receptacle, means for causing an air current or currents from said gas supply pipe to whirl up and bring along with it a quantity of fuel from the

receptacle through the fuel pipe, the adjacent ends of the pipes being arranged in such way that the said fuel transporting air current is prevented from flowing in a straight line into the fuel outlet, a member 70 for covering the outlet of said air supply pipe, said member and the discharge end of the air supply pipe being movable in relation to each other in such a way, that by adjusting one of them the outlet of the 75 air supply pipe can be wholly covered by said member, the outlet of the air supply pipe for the said fuel transporting air currents being faced upward.

3. In a feeding device for pulverulent 80 fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along with it a quantity of fuel from the receptacle through the fuel pipe, the adjacent ends of the pipes being arranged in 85 such way that the said fuel transporting air current is prevented from flowing in a straight line into the fuel outlet, a member for covering the outlet of said air supply pipe, said member and the discharge end 90 of the air supply pipe being movable in relation to each other in such a way, that by adjusting one of them the outlet of the air supply pipe can be wholly covered by said member, the outlet for the said fuel 100 transporting current being arranged laterally on said air supply pipe.

4. In a feeding device for pulverulent fuel for furnaces the combination of a powder receptacle, a fuel pipe extending from 105 said receptacle to the furnace, a pipe for supplying air or other gaseous medium into the mass in said receptacle, means for causing an air current or currents from said gas supply pipe to whirl up and bring 110 with it a quantity of fuel from the receptacle through the fuel pipe, the adjacent ends of the pipes being arranged in such way that the said fuel transporting air current is prevented from flowing in a 115 straight line into the fuel outlet, a member for covering the outlet of said air supply pipe, said member and the discharge end of the air supply pipe being movable in relation to each other in such a way, that by 120 adjusting one of them the outlet of the air supply pipe can be covered or uncovered to any desired degree by said member, the outlet of said air supply pipe consisting of a plurality of fine holes.

5. In a feeding device for pulverulent 125 fuel for furnaces the combination of a powder receptacle, a fuel pipe extending from said receptacle to the furnace, a pipe for supplying air or other gaseous medium into 130

the mass in said receptacle, means for causing an air current or currents from said gas supply pipe to whirl up and bring along with it a quantity of fuel from the receptacle through the fuel pipe, the adjacent ends of the pipes being arranged in such way, that the said fuel transporting air current is prevented from flowing in a straight line into the fuel outlet, means for 10 causing the air outlet of said air supply pipe to be covered or uncovered to any desired degree by the pulverulent fuel in the receptacle.

6. In a feeding device for pulverulent fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along with it a quantity of fuel from the receptacle through the fuel pipe, the adjacent ends of the pipes being arranged in such 20 way that the said fuel transporting air current is prevented from flowing in a straight line into the fuel outlet, one of said pipe-ends being adjustable, means for causing the air outlet of said air supply pipe to be 25 covered or uncovered to any desired degree by the pulverulent fuel in the receptacle when adjusting one of said pipes.

7. In a feeding device for pulverulent fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along with it a quantity of fuel from the receptacle through the fuel pipe, the adjacent ends of the pipes being arranged in such way, that the said fuel transporting air current is prevented from flowing in a straight 40 line into the fuel outlet, means for causing the outlet of said air supply pipe to be wholly uncovered by the pulverulent fuel in the receptacle, the outlet of the air supply pipe for the said fuel transporting air currents being faced upward.

8. In a feeding device for pulverulent fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along 50 with it a quantity of fuel from the receptacle through the fuel pipe, the adjacent ends of the pipes being arranged in such way that the said fuel transporting air current is prevented from flowing in a straight 60 line into the fuel outlet, means for causing

the outlet of said air supply pipe to be wholly uncovered by the pulverulent fuel in the receptacle, the outlet for the said fuel transporting current being arranged laterally on said air supply pipe. 70

9. In a feeding device for pulverulent fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along with it a quantity of fuel from the receptacle through the fuel pipe, the adjacent 80 ends of the pipes being arranged in such way that the said fuel transporting air current is prevented from flowing in a straight line into the fuel outlet, means for causing the outlet of said air supply pipe to be 85 wholly uncovered by the pulverulent fuel in the receptacle, the outlet of said air supply pipe consisting of a plurality of fine holes.

10. In a feeding device for pulverulent fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along 90 with it a quantity of fuel from the receptacle through the fuel pipe, the adjacent ends of the pipes being arranged in such way that the said fuel transporting air current is prevented from flowing in a straight line into the fuel outlet, the adjacent ends of said two pipes being adjustable in such a 100 way, that by adjusting one of them to a certain position the outlet of the air supply pipe can be wholly uncovered by the pulverulent fuel in the receptacle, said air supply pipe having upwardly faced discharge openings for the said fuel transporting air currents. 105

11. In a feeding device for pulverulent fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along with it a quantity of fuel from the receptacle 115 through the fuel pipe, the adjacent ends of the pipes being arranged in such way that the said fuel transporting air current is prevented from flowing in a straight line into the fuel outlet, the adjacent ends of said two 120 pipes being adjustable in such way, that by adjusting one of them to a certain position the outlet of the air supply pipe can be wholly uncovered by the pulverulent fuel in the receptacle, the outlet for the said fuel 125

transporting current being arranged laterally on said air supply pipe.

12. In a feeding device for pulverulent fuel for furnaces the combination of a powder receptacle, a fuel pipe extending from said receptacle to the furnace, a pipe for supplying air or other gaseous medium into the mass in said receptacle, a regulating sleeve within the receptacle, the longitudinal axis of which sleeve coincides with the longitudinal axis for the discharge end of the air supply pipe, a lateral outlet on said air supply pipe, said sleeve and said discharge end being movable in relation to each other in such a way, that by adjusting one of them the outlet of the air supply pipe can be covered or uncovered to any desired degree.

13. In a feeding device for pulverulent fuel for furnaces the combination of a powder receptacle, a fuel pipe extending from said receptacle to the furnace, a pipe for supplying a gaseous medium into the mass in said receptacle, one of said pipes being rotatably mounted in the receptacle, and means for varying the mutual positions of the receiving end of the fuel pipe and the delivering end of the gas supply pipe by an angular adjustment of the said rotatable pipe without displacing the pipe endwise, means for preventing the fuel from falling by gravity into the fuel pipe.

14. In a device for supplying pulverulent fuel to a locomotive furnace the combination of a tender having a powder receptacle, a pipe for supplying a gaseous medium into said receptacle, a fuel pipe extending from said receptacle to the furnace, one of said pipes being rotatably mounted in the receptacle, means for causing the air outlet of said air supply pipe to be covered or uncovered to any desired degree by the pulverulent fuel in the receptacle, means for preventing the fuel from falling by gravity into the fuel pipe, means for rotating said rotatable pipe, said means being accessible from the locomotive conductor room.

15. In a feeding device for pulverulent fuel for furnaces the combination of a powder receptacle, a fuel pipe extending from said receptacle to the furnace, a pipe for supplying a gaseous medium into the mass in said receptacle, one of said pipes being rotatably mounted in the receptacle, and means for varying the mutual position of the receiving end of the fuel pipe and the delivering end of the gas supply pipe by an angular adjustment of the said rotatable pipe without displacing the pipes endwise, means for preventing the fuel from falling by gravity into the fuel pipe, means for causing an air current or currents from said gas supply pipe to whirl up and bring along with it a quantity of fuel from the recep-

tacle through the fuel pipe, the adjacent ends of the pipes being arranged in such way that the said fuel transporting air current is prevented from flowing in a straight line into the fuel outlet, the last named means being so arranged that the receiving opening of the fuel pipe and the opening in the air supply pipe for said current lie in planes which form an angle to each other.

16. In a feeding device for pulverulent fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along with it a quantity of fuel from the receptacle through the fuel pipe, means for causing the outlet of said air supply to be wholly uncovered by the pulverulent fuel in the receptacle, the outlet for the said fuel transporting current being arranged laterally on said air supply pipe.

17. In a feeding device for pulverulent fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along with it a quantity of fuel from the receptacle through the fuel pipe, means for causing the outlet of said air supply pipe to be wholly uncovered by the pulverulent fuel in the receptacle, the outlet of said air supply pipe consisting of a plurality of fine holes.

18. In a feeding device for pulverulent fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along with it a quantity of fuel from the receptacle through the fuel pipe, the discharge end of the air supply pipe being located within the interior of the receptacle, an outlet from said discharge end to the interior of the receptacle, a member for covering said outlet, said member and the discharge end of the air supply pipe being movable in relation to each other in such a way, that by adjusting one of them said outlet can be wholly covered by said member, said outlet being arranged laterally on said air supply pipe.

19. In a feeding device for pulverulent fuel for furnaces the combination of a powder receptacle, a fuel pipe extending from said receptacle to the furnace, a pipe for supplying air or other gaseous medium into the mass in said receptacle, means for

- causing an air current or currents from said gas supply pipe to whirl up and bring along with it a quantity of fuel from the receptacle through the fuel pipe, the discharge end of 5 the air supply pipe being located within the interior of the receptacle, an outlet from said discharge end to the interior of the receptacle, a member for covering said outlet, said member and the discharge end of 10 the air supply pipe being movable in relation to each other in such a way, that by adjusting one of them said outlet of the air supply pipe can be covered or uncovered to any desired degree by said member, said outlet 15 consisting of a plurality of fine holes.
20. In a feeding device for pulverulent fuel for furnaces the combination of a powder receptacle, a fuel pipe extending from said receptacle to the furnace, a pipe 20 for supplying air or other gaseous medium into the mass in said receptacle, means for causing an air current or currents from said gas supply pipe to whirl up and bring along with it a quantity of fuel from the receptacle through the fuel pipe, the discharge end of 25 the air supply pipe being located within the interior of the receptacle, an outlet from said discharge end to the interior of the receptacle, the adjacent ends of one 30 of said pipes being adjustable, means for

causing the air outlet of said air supply pipe to be covered or uncovered to any desired degree by the pulverulent fuel in the receptacle when adjusting one of said pipes.

21. In a feeding device for pulverulent fuel for furnaces the combination of a powder receptacle, a fuel pipe extending from said receptacle to the furnace, a pipe for supplying air or other gaseous medium into the mass in said receptacle, means for causing an air current or currents from said gas supply pipe to whirl up and bring along with it a quantity of fuel from the receptacle through the fuel pipe, the adjacent ends of the pipes being arranged in such way 45 that the said fuel transporting air current is prevented from flowing in a straight line into the fuel outlet, a member forming a part of the fuel pipe and serving to cover the outlet of the air supply pipe, the two 50 pipes being movable in relation to each other in such a way, that by adjusting one of them said outlet can be covered or uncovered to any desired degree by said member.

In testimony whereof I affix my signature 55 in presence of two witnesses.
